CASTING APPARATUS FOR FILM SUPPORT OR SHEETING

Gale F. Nadeau and Alf M. Glasoe, Rochester,
N. Y., assignors to Eastman Kodak Company,
Rochester, N. Y., a corporation of New Jersey

Application April 1, 1949, Serial No. 85,001

4 Claims. (Cl. 18—15)

1

The present invention relates to the art of casting photographic film support and/or sheeting, and particularly to an apparatus for casting such film support or sheeting by depositing an evaporative-type dope onto a casting surface and obtaining a film or sheet whose surface is free from a wave-like pattern.

In the art of casting film support or transparent sheeting, it is common practise to deposit a film of dope of desired thickness onto a movable casting surface where it is set and cured and finally stripped off the casting surface in the form of a continuous sheet. Different types of dopes are used and which require certain modifications in the casting technique. For instance, there are dopes known as "gel" type dopes which are set by cooling, and are thereafter cured by the circulation of air over the set dope. Dopes of this type require a chilling of the dope immediately after deposit on the casting surface, either by cooling the casting surface or running it through a chill-box. Then there are dopes known as the evaporative type which require the evaporation or diffusion of a proportion of the solvent contained therein in order for them to become set, after which they are further cured to completely remove the contained solvents. It will be understood that since these evaporative-type dopes remain in a so-called fluid state for an appreciable time after their deposition on the casting surface, considerable care is required in handling the deposited dope up to the time it is set in order to obtain a film of uniform thickness and, hence, having perfectly smooth surfaces.

Despite all of the exacting steps heretofore taken in the manufacture of the casting surface, and the air-circulating systems used in the casting of these evaporative-type dopes, it has been found that very often a wavy pattern appears on the surface of the film support or sheet not having been engaged by the casting surface. While this wavy pattern is not too objectionable in some sheeting, it is highly objectionable in photographic film supports where the uniformity of thickness of subsequently coated light-sensitive emulsions is critical, and in transparent sheeting where optical quality is desirable and would be damaged by a wavy pattern on one of the surfaces of the sheeting.

Accordingly, the primary object of the present invention is to provide an improved casting apparatus for handling film dopes of the evaporative type which reduces, or completely eliminates, the possibility of obtaining a wavy pattern on the sheet surface as found in some film supports

2

and/or sheeting cast by the use of conventional apparatus.

Another object is to provide an improved casting apparatus of the type set forth which is so designed as to prevent eddy currents of circulating air from contacting that portion of the deposited dope which is not set sufficiently to resist being "worked" by such eddy currents of air, but still allow the solvents to diffuse or evaporate freely from the cast dope.

And, a further object is to provide a casting apparatus of the type set forth in which the freshly cast dope is protected from being directly contacted by the circulating air through the use of a fine mesh screen which is spaced slightly from the surface of the cast dope, and which allows the solvents to diffuse freely from the cast dope, said screen protecting the cast dope up to the time said dope is sufficiently set to resist being "worked" by the circulating air.

The novel features that we consider characteristic of our invention are set forth with particularity in the appended claims. The invention itself, however, both as to its organization and its methods of operation, together with additional objects and advantages thereof, will best be understood from the following description of specific embodiments when read in connection with the accompanying drawings, in which:

Fig. 1 is a side elevational view showing one form of casting apparatus constructed in accordance with a preferred embodiment of the present invention; and

Fig. 2 is an enlarged detailed view of a portion of the apparatus shown in Fig. 1 and showing in detail the protecting screen which is added to conventional casting apparatus in accordance with the present invention.

Like reference characters refer to corresponding parts throughout the drawings.

In the course of studying the various factors which contribute to the thickness uniformity of a film cast from an evaporative-type dope, either photographic film support or sheeting, we discovered that the air conditions around the green, or uncured, cast dope were of considerable importance in determining the quality of the final sheet. The mechanism by which variations in the temperature and velocity of the air passing over the uncured dope effect a change in the thickness of it is considered to be the result of the velocity of the air at the dope-air interface on the rate of curing or solvent loss from the dope. We know that when the velocity is high, there results a skinning-over of the wet or un-

cured dope; this skin being subsequently swollen and thereby extended later in the curing process when the air velocity is decreased, so that the rate of removal of solvent at the air-dope interface is relatively slower than the diffusion of solvent from the body of the uncured dope to the air-dope interface. It is possible in fact to demonstrate this phenomenon on freshly cast dope by the proper manipulation of air currents over its surface. There are small areas visible on the surface of the dope that show a wave-like pattern. This pattern is active if the air currents playing over the dope surface vary, and it is obvious that this working of the surface of the dope must necessarily lead to a movement of the viscous dope within the body of the cast uncured dope. Such a movement of the flowable dope can only lead to variations in thickness of the finally cured sheet. It is possible to see these effects in various ways by means of properly designed experiments, and it is also possible to show that air velocity and eddy currents are not effective in producing such thickness variations on a dope that is gelled or set on contact with the casting surface, and thereby render it immobile.

By reason of the fact that, from a practical standpoint, it has not been possible to design a casing around a dope casting surface, whether it be a wheel or band, of sufficient accuracy and of the proper geometrical proportions to assure absolute uniformity of air flow across the width of a normal casting wheel or band, we have approached and solved the problem in another manner. We first visualized that if the solvent could be removed uniformly over all of the surface of the cast dope by some diffusion process, free of the rapid and non-uniform movement of large bodies of air, a more nearly uniform rate of evaporation would result thereby in a film of more uniform thickness.

We discovered that such a condition could be realized by fixing a relatively fine screen parallel to the casting surface and approximately one inch therefrom; said screen being located adjacent the point of deposition of the dope on the casting surface. With this apparatus, variations in the velocity of air flow over the screen (eddy currents) did not result in the "working" of the dope which normally occurred if the dope surface was exposed to such eddy currents, or other non-uniform air flow. Under these conditions the solvent diffuses out of the dope and through the screen, the movement of the curing air over the screen effectively maintaining a low and safe solvent concentration. Since the curing process is primarily one of diffusion, the above-described procedure does not reduce the rate of curing of the dope.

Referring now to the drawing wherein a specific embodiment of the present invention is shown in association with one form of conventional casting apparatus 10 represents a large casting wheel, onto the surface of which a regulated film of evaporative-type dope 11 is fed from a hopper 12. The casting wheel 10 is rotated by any suitable drive means, not shown, in a clockwise direction at a speed dictated by its size, the nature of the film dope, and the curing effect of the air circulation system, so that when the deposited film of dope reaches stripping roll 13, the completely cured sheet "S" can be stripped from the wheel and passed over guide rollers 14 to a take-up roll, or other apparatus, not shown. In order to effect the desired curing of the cast film of dope on the wheel, it is customary to cir-

culate air, warmed or otherwise, depending upon the nature of the dope, in a carefully regulated manner over the casting surface, so as to try to eliminate deformation of the uncured film of dope on the wheel. In the embodiment disclosed this is accomplished by enclosing the wheel surface with a casing 16 which is concentric to and substantially spaced from the wheel surface to reduce any tendency to produce a high velocity of air over the wheel surface. One end of this casing is connected to an inlet pipe 17 through which air, under pressure, may be fed to the casing by a pressure fan, or other suitable means, not shown. The other end of the casing is connected to an outlet pipe 18 which is, in turn, associated by an exhaust fan 19. Accordingly, the air flow through the casing is as indicated by the arrows in Fig. 1, or through the casing 16 in a direction counter to the direction of movement 20 of the wheel surface.

All of the apparatus described up to this point is conventional and forms no part of the present invention *per se*, except as it acts in combination with, or is modified by, the new and novel structure to be hereinafter described. It will be obvious that the type of casting apparatus to which applicants' invention is applied need not be of the wheel-type, as disclosed by way of illustration, but that it could likewise be a casting apparatus using a band-type of casting surface along with any other suitable type of dope-depositing means and any other suitable type of air-circulating system.

Coming now to the present invention we fix a fine mesh screen 20 in spaced parallel relation with that portion of the casting surface adjacent the point at which the dope is deposited thereon and extending along the casting surface from the point of application of the dope to the point 40 on the surface at which the cast film of dope is sufficiently set, or cured, to resist being "worked" by eddy currents or non-uniform velocity in the circulating air passing over that portion of the casting surface. The term "worked" as used means that the cast film of dope is sufficiently uncured, or unset, to possess a mobility which would permit eddy currents or changes in the velocity of air moving thereover to cause the entire body, or at least the surface thereof, to be physically disturbed to produce a wavy or irregular surface. As shown, this screen 20 is fixed at one end to the wall of the hopper and is arcuate in shape so as to extend parallel to the casting surface of the wheel. This screen 20 is wide enough to cover the entire width of the casting surface, and the length of the uncured dope that should be protected by such screen is variable and is more or less specific for each dope, depending upon its rate of setting, the speed of the casting surface, etc. However, for most of the evaporative-type dopes now being currently used in the film-support art, a screen eight feet long appears to be sufficient. For a dope that sets fairly rapidly, this length could be reduced to as little as three feet.

We have found that a screen located relative to the casting surface as described prevents any eddy currents of air formed by variations in the velocity of air flowing over the screen from "working" the dope. On the other hand, as illustrated in Fig. 2 by directional arrows, this screen allows the solvent in the dope to diffuse out of the dope as readily as if the screen were not present, and the movement of the curing

air over the screen effectively maintains a low and safe solvent concentration in the air casing 16 and associated outlet pipe 18. Since the curing process of the dope is primarily one of diffusion, the introduction of this screen does not reduce the rate of curing of the dope.

The size of the screen mesh is definitely less critical than the length of the screen, since it is only necessary that the mesh be fine enough to prevent passage of large volumes of directed air into contact with the cast dope. In experiments we have conducted, screen sizes of 30 and 60 mesh have been used with approximately equal results. It is our conclusion that the limits as to screen size are 20 to 100 mesh, since anything finer than 100 mesh appears to prevent adequate diffusion of the solvent from the dope and unduly reduces the curing rate, while any mesh coarser than 20 fails to prevent the passage of large volumes of directed air into contact with the fresh-cast dope which are conducive to undesirable eddy currents.

With respect to the placement of the screen relative to the deposited dope surface, we feel that although not critical, however for practical reasons the screen should be substantially parallel with the casting surface and be placed approximately one inch above the dope being cured. Closer placement of the screen has been found to be impractical because of mechanical difficulties and although the screen might be positioned two or three inches above the dope, there is no practical reason for doing so.

While we have shown the screen 20 associated with a casting wheel and mounted by being fixed at one end to the wall of the dope hopper 12, it will be readily understood that a screen of this type could be associated with any type of casting surface and dope depositing means within the spirit of the present invention, since the purpose and function of the screen is not limited by its individual shape or its manner of mounting. Inasmuch as evaporative-type film dopes are many and well-known in the art, and the present invention is not limited to the use of any one thereof, it is not deemed necessary to elaborate on the manufacture, the composition, or other characteristics of these dopes. However, to give one example of a known film dope of the evaporative type which a casting apparatus, constructed in accordance with the present invention, is adapted to handle, we might mention a dope composed of one part cellulose acetate, two and one-half to three parts acetone, plus a desired quantity of a suitable plasticizer, for instance,

25 per cent diethyl phthalate based on acetone. A dope of this type is generally coated at a temperature between 120-130° F., preferably 125° F.

Although we have shown and described certain specific embodiments of our invention, we are aware that many modifications thereof are possible. Our invention therefore is not to be limited to the precise details of construction shown and described but is intended to cover all modifications coming within the scope of the appended claims.

Having thus described our invention, what we claim is new and desire to secure by Letters Patent of the United States is:

15. 1. A sheet casting apparatus comprising a movable casting surface, a hopper for depositing a uniform thin film of evaporative-type dope onto said casting surface, means for circulating air over that portion of the casting surface carrying said deposited dope to evaporate and cure the same, and a fine mesh screen, independent of said last-mentioned means, extending from the hopper in the direction of movement of the casting surface and being disposed in parallel spaced relation with said casting surface to prevent eddy currents in the circulating air from directly contacting the film of dope of said casting surface and to permit the dope to evaporate due to a diffusion action, said screen being long enough to cover that portion of the casting surface up to the point where the dope is sufficiently set to resist being "worked" by the circulating air passing over said casting surface.
20. 2. A sheet casting apparatus according to claim 1 in which the screen is one between 20 and 100 mesh.
25. 3. A sheet casting apparatus according to claim 1 in which the screen is long enough to extend at least three feet along the casting surface from the point of application of the dope.
30. 4. A sheet casting apparatus according to claim 1 in which the screen is spaced within two inches of the casting surface.
